US00D502728S

(12) United States Design Patent (10) Patent No.: US D502,728 S
Schuss (45) Date of Patent:  Mar. 8, 2005

(54) TYPE FONT

(75) Inventor: Jochen Schuss, Biedenkopf (DE)

(73) Assignee: Heidelberger Druckmaschinen AG,
Heidelberg (DE)

() Term: 14 Years

(21) Appl. No.: 29/175,113

(22) Filed: Jan. 30, 2003

(30) Foreign Application Priority Data

Aug. 24, 2002 (DE) 4 02 50 014

(51) LOC (7) Cl. 18-03

(52) U.S. Cl. D18/24

(58) Field of Search D18/24-33; 101/398,
101/399
